(57) **CLAIM**

I claim the ornamental design for a powered circular saw, substantially as shown.

DESCRIPTION

FIG. 1 is a perspective view of the powered circular saw.

FIG. 2 is a side view of the powered circular saw.

FIG. 3 is an opposite side view of the powered circular saw.

FIG. 4 is a top view of the powered circular saw.

FIG. 5 is a bottom view of the powered circular saw.

FIG. 6 is a rear view of the powered circular saw; and,

FIG. 7 is a front view of the powered circular saw.
